BEATER ROLL

Frank Hayes, Hoosick Falls, N. Y., assignor to
 Noble & Wood Machine Co., Hoosick Falls,
 N. Y., a corporation of New York

Application September 3, 1947, Serial No. 771,942

4 Claims. (Cl. 92—22)

1

My present invention relates to beater rolls, and more particularly to beater rolls for use in connection with the manufacture of paper.

Heretofore beater rolls have been constructed by building up on the roll body a filling consisting of bars and spacers. In one form of such roll, the filling was segmental, each segment being riveted together as a unit, and each segment being provided with one extending bar which fitted into a slot or keyway machined into the surface of the cylindrical roll body or shell. The individual segments were held to the cylindrical body or shell by so-called "hook" bolts spaced at intervals across the face of the shell, and at each end by cap screws turned from underneath the roll shell.

While this construction was practical it was never entirely satisfactory, because it was difficult to turn in the so-called "hook" bolts so that the contacting surfaces were on an exactly even plane across the face of the roll; it was difficult to locate the holding rods, which were built into the segments themselves, so that these were equally spaced from the bottom of the segment to the center of the holding rod; and because each of the segments was of all metal construction, and in order to assure absolutely tight roll filling construction, with no vibration or working of the various individual segments, the sides must necessarily mate exactly one to the other a mechanical job difficult enough in a shop and even more so when making replacements in the field.

With this type of filling, failure in service was apt to occur when there was lack of proper contact on all the "hook" bolts across the face of the roll in various segments, or lack of proper side bearing, segment to segment, or both. Under such conditions, some of the segments might work, or lean sidewise, when submitted to bed plate pressures, resulting in undue strain being placed on the fixed cap screws holding down the segments on the end, with the consequent shearing off of such screws.

In my present invention, I have obviated the faults in such prior construction by eliminating the necessity for machining longitudinal slots in the roll body and by eliminating the use of unit segments comprised of a plurality of spacers and roll bars.

According to my present invention I provide the roll body with only enough slots to divide the peripheral surface thereof into zones, mount on the roll body both roll bar and spacer locking means, and build up the filling out of individual roll bars and spacers.

2

By this construction I am able to individually lock each roll bar and each spacer to the roll body at a plurality of points along their length, and by dividing the surface of the roll body into zones I may remove any individual roll bar or spacer from the assembly for repair or replacement without disturbing any of the other elements. This construction not only makes for a better beater roll, but one which may be successfully repaired without removal from the machine.

The principal object of my invention is therefore an improved beater roll for beaters and like refineries.

15 Another object is an improved filling for beater rolls by means of which a maximum number of roll bars may be employed and a minimum spacing between bars may be obtained, thereby reducing to the minimum the slotting of the roll.

20 Another object is an improved beater roll in which the number of roll bars, as well as the thickness thereof, and the spacing between said bars, may be varied. With a slotted roll, it is not possible to vary the number and spacing of the roll bars.

25 Another object is an improved beater roll in which the filling, comprised of the roll bars and spacers, can be removed and/or replaced without the necessity of removing the beater roll from the beater.

30 Another object is an improved beater roll in which any individual roll bar or spacer can be removed and/or replaced without disturbing any of the remaining roll bars or spacers.

35 A further object is an improved beater roll in which the roll bars are mounted directly upon the outer circumferential face of the roll body.

40 Another object is an improved beater roll in which the circumference of the roll body is divided into segments or zones by spacers set into slots formed in the roll body and extending parallel to the axis thereof, and in which said spacers are removably locked in position on the roll body.

45 Other objects and novel features of the construction and arrangement of parts comprising my improved beater roll will appear as the description thereof progresses.

In the accompanying drawings illustrating a preferred embodiment of my invention:

50 Figure 1 is a fragmentary end elevational view, partly in section, of the upper portion of a beater roll.

Figure 2 is an end elevational view of the assembled beater roll.

55 Figure 3 is a side elevational view showing one

of the segment dividing bars for dividing the periphery of the roll body into segments or zones; and

Figure 4 is a vertical section through the beater roll.

Referring to the drawing 10 designates a beater roll shaft, on which is secured the roll body 11. Roll body 11 may be a single shell, or may be built up of a plurality of spiders or heads 12 arranged end to end, or spaced apart from each other and rigidly secured to shaft 10.

With the common type of slotted rolls, it is customary to provide slots in these spiders of proper size and number to accommodate the size and number of fly bars designated. It will be apparent therefore that while the thickness of the fly bar may conceivably be varied at the cutting or working edge, the size of that portion fitting into the slot or the number of bars in the roll or the spacing between the bars cannot be varied. It also is generally necessary to fill such rolls with wood spacers or wedges driven between the bars and projecting below the bars, the swelling of the woods being depended upon to solidly hold the bars in place and to anchor the woods beneath the bars to prevent them from working out in operation.

In my new roll I build up the roll body from individual heads or spiders pressed on the spindle or shaft much the same as in the common types of beater rolls but instead of these heads being turned in steps on their outer peripheral surfaces I turn these outer surfaces flat and on a perfect plane across the face of the roll. After this turning operation is completed I machine approximately sixteen slots 13 across the face of the roll, dividing the roll into sixteen equal segments on the circumference. A forged band or hooked ring 14 is then shrunk on each of the inside heads (number of heads depending on length or face of roll) and the under surface of this band where the "hook" is formed, marked 15, is accurately machined in relation to the outside circumference of the roll heads.

Referring to Fig. 3, there is shown in side elevation, a metal segment spacer bar 16 having cut-out portions 17 intermediate its ends and provided with hook member 18 for engaging the under face of the hook portions 15 of the bands or rings 14. At their ends, bars 16 are provided with hook members 19 for a purpose to be herein-after described.

In filling the roll, sixteen segment spacer bars 16 of the proper thickness and width, are inserted into the grooves 13 and then driven to contact position under the hook members 15 of the bands or rings 14. This divides the surface of the roll body 11 into sixteen equal segments.

For clearness of description it will be understood that the roll being described will contain one hundred and ninety two cutting bars three-sixteenths thick, with equal spacing approximately .6715" at bar edges so that each of the sixteen segments will contain twelve cutting bars and eleven metal or wooden spacers. These figures are illustrative merely, and it is to be understood that the number of segments may vary with an increase in the diameter of the roll body, and also the number of cutting bars may vary under like conditions.

The segments are filled with cutting bars 20 and intermediate spacer bars 21, illustrated in end section in Fig. 1, but the side elevation of the segment spacer bar 16 in Fig. 3 illustrates equally

well the construction, in side elevation, of the cutting bars 20 and intermediate spacer bars 21.

Filling of the segments will progress from the fixed holding spacers 16 at the end of each segment, working towards the center of that segment, installing first a cutting bar 20 and then an intermediate spacer 21, and driving each bar and each spacer tight against its neighbor, with the hook members 18 locking under the hook portion 15 of the bands or rings 14. This continues until all but the last intermediate spacer 21 has been installed.

It may be presumed that there will be some variation in the rolled thickness of the cutting bars 20, and the final intermediate spacer may have to be machined to proper size to draw up tightly this final segment of filling.

As stated above Fig. 3 may serve equally well to illustrate the segment spacer 16, the intermediate spacers 21 and the cutting bars 20. The intermediate spacer bars 21 differ only from the segment spacers 16 in that they are narrower and rest on the surface of the roll body, whereas the segment spacers 16 seat in the grooves 13. (See Fig. 4.) Also the cutting bars 20 are wider than the spacers 16 and 21, as such bars extend outwardly beyond the spacers to form the cell pockets for the stock being treated. (See Fig. 1.)

In the filling described, the intermediate spacer bars 21 may be $2\frac{3}{4}$ " wide and their ears, which drive under the holding bands, may be shallower by $\frac{1}{2}$ ". The cutting bars 20 may be $3\frac{1}{2}$ " wide to project $\frac{3}{4}$ " beyond the spacers to form the cell pockets. However, instead of using cutting bars which are $\frac{13}{16}$ " thick, I may use other bar thicknesses, as for example $\frac{1}{4}$ " or $\frac{1}{8}$ ", with the same spacers, and vary the number of bars in each segment to compensate for the change in thickness, and utilize the size of the final fitted spacer in each segment to compensate for irregularities in spacing. Of course, it will be understood that with wooden spacers, swelling takes care of minor variations in thickness.

The remaining segments are filled in the manner above described. When this operation is completed, the hook members 19 in the cutting bars 20 and spacers 16 and 21, come into alignment, and provide a continuous groove 22 on the end face of the assembly.

23 designates holding members—of which there are eight equally spaced about and on each end of the assembly. These holding members 23 are provided on their inner surface, top and bottom, with arcuate projections 24 and 25 respectively. The arcuate projections 24 seat in the grooves 22 formed in the ends of the spacers and cutting bars, and the arcuate projections 25 seat in a circular groove 26 formed in the end of the roll body 11. The holding members are driven and securely anchored in place by a series of flat head machine screws 27 screwing into the roll body 11.

A renewable and removable wearing plate 28 may be secured to the outside ends of the roll body 11 by screws 29 to entirely cover the ends of the roll, the holding members 23 and the ends of the bars and spacers. Preferably this wearing plate 28 is made in sections. If desired I may interpose a suitable gasket between the ends of the bars and spacers and the inner face of the holding members 23.

After the beater roll is installed in a beater, and should it become necessary to replace the filling of bars and spacers, or to renew damaged cutting bars, the attendant need only remove the hood

or curb from the beater, remove that segment of the wearing plate 28 and holding member 23 which are adjacent to the section holding the parts to be removed, remove the final fitted spacer in such segment, whereupon each bar and spacer may be easily driven back from beneath the band or ring 14. The damaged bar or spacer, or each or all of them in a segment can then be replaced and a fitted wedge spacer driven to securely lock the elements in position. The same procedure would follow for the complete roll if entire renewal is necessary.

The spacers, preferably of metal, need not be renewed, but can be used over and over with the exception of the one fitted spacer, and the last to be installed in a segment. For ease in fitting, particularly on the job, this spacer may be made of some fibrous material and preferably of a non-splinterable wood; indeed, in some installations it may be preferable to use a majority of wooden spacers.

Having thus described my invention, what I claim as new is:

1. In a beater roll, the combination of a shaft, a roll body having a machined surface of a predetermined radius mounted thereon for rotation therewith and having a plurality of grooves extending longitudinally thereof and dividing the surface of the body into segments, locking rings secured to the surface of the body and spaced along the length thereof, segment separating spacers seating in said grooves and locked to the body by the locking rings, and a filling for each of the segments comprising a plurality of intermediate spacers and cutter bars arranged alternately in the segment, locked to the locking ring, and with their lower ends in engagement with the surface of the roll body.

2. In a beater roll, the combination of a shaft, a cylindrical roll body having a machine surface of a predetermined radius mounted thereon for rotation therewith, and having a plurality of grooves extending longitudinally thereof parallel to the shaft and dividing the surface of the body into segments, locking rings secured to the surface of the body and spaced parallel to each other along the length thereof, segment separating spacers having their lower edges seating in said longitudinal grooves and with the body of said spacers extending radially outward from the roll body, said spacers locked to the roll body by the locking rings, a filling for the segments comprising a plurality of intermediate spacers and cutter bars alternately arranged in the segments, locked to the roll body, and with their lower edges in engagement with the surface of the roll body, there being a circular groove formed in the end of the spacers and cutting bars, and a segmental covering for the end of the spacers and cutting bars secured to the end of the roll body.

3. In a beater roll, the combination of a shaft, a cylindrical roll body having a machined surface of a predetermined radius mounted thereon for rotation therewith, and having a plurality of grooves extending longitudinally thereof parallel to the shaft and dividing the surface of the body into segments, locking rings secured to the surface of the body and spaced parallel to each other along the length thereof, segment separat-

ing spacers having their lower edges seating in said longitudinal grooves and with the body of said spacers extending radially outward from the roll body, said spacers locked to the roll body by the locking rings, a filling for the segments comprising a plurality of intermediate spacers and cutter bars alternately arranged in the segments, locked to the roll body, and with their lower edges in engagement with the surface of the roll body, there being a circular groove formed in the end of the roll body and a circular groove, concentric with said first-named groove formed in the end of the spacers and cutting bars, and a covering for the end of the spacers and cutting bars comprising segments each having arcuate projections on their inner surface, top and bottom, the top projection fitting into the circular groove formed in the end spacers and cutting bars, and the bottom projection fitting into the circular groove formed in the end of the roll body, and means for securing said segments to the roll body.

4. A beater roll comprising a cylindrical body having a machined surface of a predetermined radius, walls forming a plurality of grooves in said surface, said grooves extending longitudinally of said body and being spaced to divide said surface into equal segments, a plurality of retaining rings secured to the surface of said body, a flange on said rings defining a hook portion for said rings outward of said surface, machined steel segment spacers adapted to fit in said grooves and being notched on their inner margins to define hook portions therein complementary in shape to the hook portions defined by said rings, said segment spacers being retained by said rings with said hook portions of both interlocking, cutter bars and bar spacers adapted to abut the machined surface of the body throughout its length and being notched on their inner margins to define hook portions complementary in shape to the hook portions defined by said rings, said cutter bars and said bar spacers being arranged alternately between said segment spacers, and being retained by said rings with the hook portions of the said bars and bar spacers interlocking with the hook portions of said rings, and a plurality of segmental holding members secured to each end of said body, said holding members each adapted to abut the ends of said cutter bars, bar spacers, and segment spacers and to retain the same, and said holding members each covering only the space of a single segment.
